APPLICATOR FOR GUMMED REINFORCEMENTS

Eugene Forshey, San Diego, Calif.

Application August 2, 1955, Serial No. 526,040

1 Claim. (Cl. 216—34)

The present invention relates generally to applicators and more particularly to an applicator for annular gummed reinforcements, rings or patches commonly employed to reinforce the pages of loose leaf notebooks and the like at the edges of the apertures punched therein to receive the attachment rings of the notebook.

The primary object of this invention is to provide a device to apply gummed reinforcements to paper.

Another object of this invention is to provide an applicator which will hold a supply of gummed reinforcements stacked on a magazine element, in readiness for application.

Another object of this invention is to provide an applicator wherein the stacked reinforcements are held loosely in order to prevent adherence to each other.

Another object of this invention is to provide an applicator so constructed as to prevent inadvertent removal of the stacked reinforcements.

Another object of this invention is to provide an applicator which in use will not damage underlying surfaces such as a desk top, or papers thereon.

Another object of this invention is to provide an applicator which supplies sufficient uniformly distributed pressure upon the peripheral portion of the gummed reinforcements to assure adherence of said reinforcements to the page of the notebook or other article being processed.

Another object of this invention is to provide an applicator which is adapted for fabrication from many different materials, so that the choice of material can be according to the dictates of availability and price considerations, the exact sizes and proportions being matters easily determined to suit particular conditions and needs.

Another object of this invention is to provide an applicator which is practicable and inexpensive to manufacture.

Finally, it is an object to provide an applicator of the aforementioned character which is simple, safe and convenient to use and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure, and in which:

Figure 1 is longitudinally sectioned view of the applicator in extended position.

Figure 2 is a longitudinally sectioned view similar to Figure 1, but showing the parts in fully closed position, as when under pressure.

Figure 3 is a fragmentary, enlarged view, largely in section showing the lower end portions of the applicator with a plurality of annular gummed reinforcements positioned on the magazine element of the applicator, the parts being illustrated in the positions thereof assumed

2

when the lowermost of said reinforcements is being applied.

Figure 4 is a fragmentary, enlarged view of the upper portion of the magazine, showing the beveled portion, and 5 a tool providing a rapid and easy loading of gummed reinforcements on the magazine when the same has been removed from the tool.

Similar characters of reference indicate similar or identical elements and portions throughout the specification 10 and throughout the views of the drawing.

In substantially all business there is at times a need for the application of annular gummed reinforcements to prevent the tearing of paper in which holes are punched for the purpose of mounting a sheet or sheets of paper in a ring binder or the like. This necessitates several steps, the first of which is a search for a container in which the gummed reinforcements are stored. Next, the removal of a single reinforcement from the container, then moistening the paper or the gummed reinforcement in some manner, then applying the reinforcement to the paper.

Any one of these steps may present difficulties which are time-consuming and, therefore, expensive.

The present invention provides a means to store, moisten, and apply the gummed reinforcements with great rapidity, thereby at least facilitating the previously mentioned steps.

Referring now to the drawings there is shown a housing 10 of generally hollow cylindrical form having a head 12 of a larger diameter than and fixed normal to the upper end of the housing 10. The head 12 presents a flat interior surface to which is attached a sponge rubber moistening head 14, and an interior surface to which is fixed a guide member 16 in internal coaxial relationship 30 with the housing 10 and the head 12. The guide member, as illustrated, extends throughout approximately one-half the length of the housing 10. The housing 10 is enlarged in diameter at the end opposed to the head 12 to constitute a pressure head 20 having a substantially flat face 18. The pressure head 20 is also provided with a bore 22 of slightly larger diameter than the internal diameter of the housing 10. Adjacent the face 18, the pressure head has a bevelled portion 23.

45 A magazine 24 is provided, this magazine being of hollow cylindrical form and of an external diameter to allow insertion thereof into the previously mentioned housing 10. The magazine has sliding relationship with the previously mentioned guide member 16. A compression 50 spring 26 is mounted coaxially on the guide member 16 and compressed between the upper end of the magazine and the inner face of the head 12 to bias the magazine outwardly or downwardly. The magazine 24 is maintained against withdrawal from the housing 10 by a key 55 28 and slot 30 arrangement. The key 28 is a protrusion on the surface of the magazine, and of a shape and dimension to allow passage thereof through the slot 30 in an annular bead or ring 32 on the inside of the housing 10 adjacent the inner end of the bore 22. The magazine 60 24 may be removed from or inserted in to the housing 10 by rotating the magazine 24 until the key 28 is in alignment with the slot 30, and moving the magazine 24 axially in relationship with the housing 10. After insertion, the magazine 24 is rotated so that the key 28 is no longer in alignment with the slot 30. Since substantially no rotational movement of the magazine 24 is caused by operation of the device, the magazine 24 will be retained against inadvertent removal.

65 The upper end 34 of the magazine 24 is tapered slightly to facilitate placing the gummed reinforcements 36 on the magazine, the external diameter of the magazine being considerably less than the diameter of the apertures in the

gummed reinforcements to be used therewith, as clearly indicated in Figure 3, and the lower end 38 of the magazine 24 is belled outward sufficiently to prevent inadvertent removal of the gummed reinforcements 36 therefrom. Further mention of the belled lower end 38 of the magazine 24 will be made later in this disclosure.

At a point a distance axially inward of the belled lower end 38 of the magazine 24, there is a retaining washer 40 fixed, by solder or the like, to the magazine and a small compression spring 42 is compressed between this washer 40 and a retractable guide pin 44 which extends through the belled lower end 38 of the magazine 24. The guide pin 44 is hollow and generally cylindrical in shape, and is provided with a portion 46 of enlarged diameter at the upper end thereof of sufficient axial dimension to prevent axial tilting when the guide pin 44 is in an extended position. The enlarged portion 46 forms a shoulder of sufficient proportions to prevent axial movement of the enlarged portion 46 past an annular, inwardly extending bead or ring 50 which, as represented, may be unitary with the magazine and disposed slightly axially inward from the belled end 38 of the magazine 24. A tip 52 of rubber or the like is attached to the end of the guide pin 44 to prevent slipping, and to prevent injury to any underlying surface, such as a desk top or the like. An external sleeve 54 of rubber or the like is provided on the housing 10 so as to provide a comfortable hand grip for the operator.

In use, the applicator is operated in the following manner. The magazine 24 is first removed from the housing 10 in a manner described hereinbefore, and a considerable number of gummed reinforcements 36 are placed over the tapered portion of the upper end 34 of the magazine 24. The gummed reinforcements 36 fit loosely on the magazine and slide down the magazine 24 until the lowermost reinforcement engages the belled end 38, the diameter of the belled end 38 being very slightly larger than the inner diameter of the gummed reinforcements 36. The magazine 24 when filled is inserted into the housing 10 in a manner previously described in this disclosure, and the applicator is ready for use.

The paper surrounding the hole to be reinforced is first dampened by means of the sponge rubber moistening head 14.

The applicator is now reversed, and the rubber tip 52 is located in the hole to be reinforced. The tip 52 is removable and when removed the outer end of the hollow guide pin can be inserted over the upper ends of vertical page-holding pins found in certain types of loose leaf notebooks and the like. A vertically downward load is applied to the housing compressing the small compression spring 42 and forcing the guide pin to slide axially within the magazine 24, bring the belled end 38 in contact with the edge of the paper surrounding the hole to be reinforced. The housing 10 continues to move in a downward direction until the pressure head 20 bears directly on the uppermost reinforcement 36 on the magazine 24, as best shown in Figure 3, said load being directed through the stacked reinforcements 36 to the one in contact with the paper to be reinforced, and sufficient peripheral pressure is applied to cause the lowermost reinforcement 36 to adhere securely to the moistened paper, in alignment with the hole therein.

The inner edges of the stacked reinforcements 36 are stretched slightly and forced upwardly by the action of the belled end 38 until the inner periphery of the lowermost reinforcement is forced over the belled end 38.

When the vertical downward load is removed from the housing 10, the small compression spring 42 produces axial sliding motion in the guide rod 44, returning the said pin 44 to operable position and, simultaneously, the compression spring 36 moves the magazine 24 in a downward direction with respect to the housing 10, allowing the stacked reinforcements 36 to separate slightly due to the natural curling tendency inherent therein, thereby preventing said reinforcements 36 from adhering to one another. The applicator is now ready for repetition of the foregoing operation.

Referring now specifically to Fig. 4, there is shown the upper end 34 of the magazine 24, removed from the housing 10. A loading tool 58 is shown in position to be inserted into the upper end 34 of the magazine 24. The reinforcements 36 are placed on the tool 58 and the loading operation consists merely of inserting the end 60 of the tool 58 into the magazine 24 until the shoulder 62 rests upon the upper end 34. The reinforcements 36 are slideably mounted on the barrel 64 and may readily be moved from the barrel 64 onto the magazine.

The operation of this invention will be clearly comprehended from a consideration of the foregoing description of the mechanical details thereof, taken in connection with the drawing and the above recited objects. It will be obvious that all said objects are amply achieved by this invention.

Further description would appear to be unnecessary. It is understood that minor variation from the form of the invention disclosed herein may be made without departure from the spirit and scope of the invention, and that the specification and drawing are to be considered as merely illustrative rather than limiting.

I claim:

An applicator for annular gummed reinforcement patches, said applicator comprising: a housing having a pressure head at one end, and a bore extending through said pressure head and a major portion of the housing; a magazine telescoped in said bore and extending outwardly beyond said pressure head when in operative position; an enlargement on the outer end of said magazine to prevent inadvertent removal of reinforcement patches stacked thereon during use of the applicator; and a guiding pin telescopically and resiliently mounted on the outer end portion of said magazine, said guiding pin being hollow and having a tip of resilient material, said tip being removable to adapt the guiding pin for insertion over the upper ends of vertical page-holding pins found in certain notebooks of loose-leaf type.
